CLAIM

The ornamental design for a thermoplastic bag pack, as shown and described.

DESCRIPTION

FIG. 1 is a perspective view of a thermoplastic bag pack showing our new design;

FIG. 2 is a bottom plan view on a reduced scale;

FIG. 3 is a side elevational view on the same scale as

FIG. 1;

FIG. 4 is a top plan view on the same scale as FIG. 2;

and

FIG. 5 is an elevational view on the same scale as FIGS.

2 and 4 showing the side opposite that seen in FIG. 1.

FIG. 3

FIG. 1

FIG. 4

FIG. 5

FIG. 2
